UNITED STATES PATENT OFFICE.

ALBERT F. SAUNDERS, OF SYRACUSE, NEW YORK, ASSIGNOR TO T. N. BENEDICT MFG. CO., OF EAST SYRACUSE, NEW YORK.

DESIGN FOR A SPOON.

49,527.

Specification for Design. Patented Aug. 15, 1916.

Application filed November 30, 1915. Serial No. 64,363. Term of patent $3\frac{1}{2}$ years.

To all whom it may concern:

Be it known that I, ALBERT F. SAUNDERS, a citizen of the United States, residing at 106 Rugby road, city of Syracuse, county of Onondaga, and State of New York, have invented a new, original, and ornamental Design for a Spoon, of which the following is a specification, reference being had to the accompanying drawing, forming part thereof.

The two figures are plan views of the front and the back of a spoon showing my new design.

I claim:

The ornamental design for a spoon as shown.

ALBERT F. SAUNDERS.
